UNITED STATES PATENT OFFICE.

GEORGE W. WRIGHT AND PATRICK W. CASEY, OF NORWICH, CONNECTICUT.

FEED-WATER HEATER.

No. 850,707.

Specification of Letters Patent.

Patented April 16, 1907.

Application filed August 20, 1906. Serial No. 331,277.

To all whom it may concern:

Be it known that we, GEORGE W. WRIGHT and PATRICK W. CASEY, both citizens of the United States, and residents of Norwich, in the county of New London and State of Connecticut, have invented a certain new and useful Improvement in Feed-Water Heaters, of which the following is a specification, reference being had to the accompanying drawings.

The chief object of this invention is to provide in a single device simple and inexpensive means for protecting the fronts of steam-boilers which will also serve incidentally as a feed-water heater.

In order to explain our said invention clearly, we have provided the annexed drawings, in which Figure 1 is a front end view of a steam-boiler and furnace embodying our present improvements, and Fig. 2 is a detached and relatively enlarged perspective view of the feed-water-heating apparatus.

Referring to the drawings, the letter *a* indicates the boiler proper, *b* the front, in which the feed-door opening is located, and *c* denotes a base-plate located in said feed-door opening and serving as a support for our combined protective device and feed-water heater.

Our device is here shown as applied to a "double-door" opening, and it includes hollow rectangular castings *d d'*, seated upon the opposite ends of plate *c*, and a similar hollow casting *d²*, located midway between the castings *d d'*.

The castings *d d'* provide water-chambers at the outer sides of the feed-door openings, and the casting *d²* provides a like water-chamber between the two feed-door openings. Chambers *d'* and *d²* are connected near their upper portions by pipes *e e'*, and the chambers *d²* and *d* are similarly connected by pipes *e² e³*, as is best seen in Fig. 2 of the drawings. The lower portion of chamber *d* is connected with the upper part of the boiler *a* by a pipe *f*. The letter *g* indicates a pipe that leads downwardly from boiler *a* and is connected with a feed-water-supply pipe *g'*, that includes a cut-off valve *h* and a check-valve *h'*, which will allow the water to enter

through pipe *g'*, but will be closed automatically by back pressure in said pipe.

Extending laterally from pipe *g* is a branch pipe *k*, that passes across the tops of the three chambers *d'*, *d²*, and *d* and back again and thence downwardly to a point near the bottom of chamber *d'*, where it enters said last-named chamber.

In the line of pipe *g* we have located a cut-off valve *m* and a check-valve *m'*. Valve *m* is ordinarily left open, so that the water may circulate from boiler *a* downwardly through pipe *g*, thence through pipe *k* and chambers *d' d² d*, and finally back to boiler *a* through pipe *f*. When it is desired to utilize our described device as a feed-water heater, the valve *m* is closed and valve *h* opened, when a fresh supply of water enters through pipe *g'*, and being cut off from direct communication with the boiler *a* (by reason of the closed valve *m*) said water passes through pipe *k*, and during such passage it becomes heated almost to the point of boiling before it enters chamber *d'*. After a sufficient quantity of water has been fed into the boiler the valve *h* is closed and valve *m* is opened, when the water from boiler *a* continues to circulate through pipes *g*, *k*, and *f* and through chambers *d'*, *d²*, and *d*, as we have already described.

The pipe *k*, being carried back and forth upon the tops of the chambers *d'*, *d²*, and *d*, forms a substantial support for the brick-work immediately over the feed-openings in the furnace-front, and thus locates said pipe where it is exposed to the influence of the hottest portions of the furnace-fire when the feed-doors are closed, thus raising the temperature of the water first fed through said pipe to the steaming-point before it is discharged into the water-chamber *d'*.

The continuous circulation of water through the chambers *d' d' d²* prevents the burning out of the side walls of the feed-opening. This feature, however, we do not claim, broadly, as of our invention, as water-jacketed side walls have been utilized heretofore; but the novelty of our present invention consists chiefly in combining with said water-jackets feed-water-heating apparatus where-

by the water is raised to the point of steaming before it is discharged into the chambers forming said water-jackets.

Having thus described our invention, we

5 claim—

In combination with a boiler and the feed-opening of a furnace, water-chambers forming the side walls of said opening, connections between said chambers and the boiler, 10 a feed-water pipe discharging into one of said

chambers, and means between said feed-water pipe and said chambers whereby the water is heated before being discharged into said chambers.

GEORGE W. WRIGHT.
PATRICK W. CASEY.
